RENÉ FRANÇOIS HENRI CAILLAUD, OF ST. MAURICE, FRANCE, ASSIGNOR TO SOCIETE ANONYME DES ETABLISSEMENTS LUTERAAN, OF PARIS, FRANCE

KNIFE-EDGE BEARING

Application filed October 20, 1928, Serial No. 313,835, and in France November 7, 1927.

The knife edges of the levers of weighing machines and other apparatus are subject to wear, and it may become necessary to repair or to replace the knife edge.

5 In view of the fact that in the construction of weighing and other machines provided with knife edge levers it is necessary that the line passing through the edges of the knives shall be a straight line, and that the 10 wear of one or more knives will produce a broken line, and that on the other hand the wear may cause differences in the axial position, it is desired to obviate these two defects.

However, in the known construction of 15 knife edges and the mounting of the same upon the levers the device cannot be adjusted at the same time for the level and for the axial position.

The present invention relates to a method 20 of mounting of the knives by which the device can be adjusted simultaneously for the level and for the axial position.

The said method is essentially characterized by the fact that the knives are mounted 25 upon their supporting lever by means of a mechanical connecting device so disposed that by its adjustment, the axis of the knives may be given displacements relatively to axes of co-ordinates placed at right angles, 30 whose origin is situated upon the axis of the assembling holes of the corresponding lever.

In the appended drawings and by way of example:

Fig. 1 shows the known arrangement of a 35 triangular knife edge, and Fig. 2 shows the same on a larger scale.

Fig. 3 shows a modification of this device in which the knife edge may be rotated for the adjustment of the axial position.

40 Fig. 4 is a front view of the knife edge.

Figs. 5 and 6 show a cross section of the lever and of the tapered shank for securing the knife.

Fig. 7 shows the device according to the 45 invention.

Figs. 8 and 9 represent a front view of the knife and a cross section of the lever, as well as the arrangements for changing the position of the said knife.

50 As a rule, the triangular knife edge 1 is

driven by tight friction into a lever or scale beam 2 which is provided for the purpose with a dovetail mortise (Fig. 2).

After grinding one or both sides of the knife edge 1 when the edge has become worn, 55 it will be impossible to place the edge at the centre and at the proper level by mechanical means, so that the scale beam must be bent by impact or pressure, although both these means are unadvisable from a mechanical 60 standpoint.

Attempts have been made to partially obviate these defects by mounting the knife edge by means of a tapered joint (Figs. 4, 5 and 6) and herein the knife edge 1 is provided with a tapered shank adapted for insertion into a recess 4 of like shape which is formed in the lever 2.

This arrangement is superior to the preceding since the device can be centered by 70 turning the knife 1 according to the arrows *a a* (Fig. 4) about the axis *z-z* of its recess 4 in the lever 2. Due to this freedom of motion the axial position can be properly regulated, but the device can only be adjusted 75 for the level by the permanent deformation of the lever by shocks or pressure.

The arrangement according to the invention permits the adjustment of the axial position and of the level at the same time. For 80 this purpose, I dispose between the recess 4 of the lever 2 and the shank 3 of the knife edge 1, a connecting device having two different motions, so that the displacements of 85 said device relatively to the lever 2 will cause the movements of the axis of the said shank of the knife blade with reference to two rectilinear axes of co-ordinates *b c* whose point of origin *o* is situated on the axis *z-z* of the 90 said recess 4 of the lever 2.

By way of example, the apparatus may be constructed as follows.

In the recess 4 of the lever 2 is disposed a ring 5 which has a cylindrical form at the exterior and is provided with a tapered hole 95 6 in eccentric relation to the outer circumference of the ring 5. The knife edge 1 is provided with a tapered shank 3 having at the end the round threaded part 7. The smooth portion 3 is adapted for an exact fit 100

with the hole 6 of the said ring; the threaded part 7 extends outwardly of the latter, so that the knife edge 1 may be securely held by the nut 8 mounted on the said threaded end 7 of the knife edge.

5 The ring 5 is split upon a single generatrix in order to provide a tight fit upon the round part of the ring 5 and also upon the tapered part of the knife edge.

10 The device is mounted as follows:

(a) The knife is mounted with the edge at the top. The knife 1 is so disposed that the smallest thickness of the eccentric ring is at the lower part (Fig. 8). Should it be necessary to make repairs due to the wear of the knife edge, the edge of the knife 1 can be sharpened by grinding on a stone. When this operation has been performed, the nut 8 holding the knife in its recess is loosened, 15 and said knife is turned so as to properly 20 adjust the axial position, at the same time rotating the ring 5 to the proper degree for the adjustment of the level with reference to the other knife edges of the same lever 1. 25 By this simple means I obviate all bending of the scale beam according to the usual method.

(b) The knife is mounted with the edge at the bottom. The knife is so disposed that the smallest thickness of the eccentric ring 30 5 is at the upper part, and the rest of the operation is performed as above mentioned.

I claim:

35 The combination of a knife edge with an eccentric bearing support comprising a main support having a circular opening therein, a bearing sleeve mounted in said opening and having an opening eccentric to said first mentioned opening, a knife edge having a tapered 40 shank fitting said opening, and means for securing said tapered shank in the opening in any angular position, whereby by turning both the bearing sleeve and knife edge said edge may be moved in a vertical direction.

45 In testimony whereof I affix my signature.

RENÉ FRANÇOIS HENRI CAILLAUD.
